[57] CLAIM

The ornamental design for a swivel picture frame, as shown and described.

DESCRIPTION

FIG. 1 is a top view of the swivel picture frame;
FIG. 2 is a front elevational view of the swivel picture frame
the rear being identical thereto;

FIG. 3 is a side view of the swivel picture frame the opposite
side being identical thereto;

FIG. 4 is a bottom view of the swivel picture frame;

FIG. 5 is a first perspective view of the swivel picture frame;

FIG. 6 is a second perspective view of the swivel picture
frame; and,

FIG. 7 is a perspective view of an alternate embodiment of
the swivel picture frame.

The broken line portions of FIG. 2 are for illustrative
purposes only and form no part of the claimed design.
